UNITED STATES PATENT OFFICE.

MALVIN LICHTER, OF NEW YORK, N. Y.

BANK BOOK.

1,419,065.

Specification of Letters Patent. Patented June 6, 1922.

Application filed May 19, 1920. Serial No. 382,570.

To all whom it may concern:

Be it known that I, MALVIN LICHTER, a citizen of the United States, residing in New York city, in the county of New York and State of New York, have invented certain new and useful Improvements in Bank Books, of which the following is a full, clear, and concise description.

My invention relates to bank books, my more particular purpose being to produce a bank book of such structure and arrangement as to adapt it for use in holding securely a limited number of coins of small denominations, the total of such coins foot-ing up a predetermined round sum, say one dollar or two dollars, the housing of the coins being so effected as to prevent them from rattling as well as from wedging together; and in doing this I also seek to have the coins in such condition that they may readily be counted by merely opening the book.

A further object of my invention is to make provision for enabling the book as a whole to be used as a deposit book for general purposes, and more particularly as a record for itemizing deposits made from time to time by simply handing in the book, with its content of coins, to the receiving teller.

Still another object of my invention is to give the bank book such construction and arrangement as will tend to make its normal use attractive to young persons, or in other words I seek to confer upon the book, to some extent at least, the functions of a toy bank.

Reference is made to the accompanying drawing forming a part of this specification, and in which like letters indicate like parts throughout the several figures.

Figure 1 is a plan view of one form of my improved bank book, showing it as open.

Figure 2 is a substantially central cross section through the form of the book appearing in Figure 1, but showing it as partially closed.

Figure 3 is a cross section, somewhat similar to Figure 2, but of another form of my book.

Figure 4 is a cross section through still another form.

Figure 5 is a perspective of the form of my bank book shown in Figure 3.

Figure 6 is a fragmentary perspective of the form of my bank book appearing in Figure 4.

Figure 7 is a plan view of the bank book as it appears when closed, this view being the same for any form of the device.

A sheet 8 of leather, leatheroid, or cardboard or tough paper, cloth, or other sheet material, preferably colored, is creased along its middle, as shown, and serves as the book back.

Secured to the inner faces of the book back are a pair of coin cards, 9, 10. These coin cards are made of thick sheet material, preferably cardboard or pasteboard.

In instances where the book is to be made up expensively, for example where it is to be marketed as a souvenir or sold for use as a Christmas present or as a toy bank, it may be made up wholly or in part of such materials as celluloid, thin and durable tree bark, sheet cork, or even sheet metal.

Each coin card 9, 10 is provided with a number of coin compartments 11, 12, 13, of different sizes, each compartment being of the exact size required to enable it to hold securely a standard and popular coin of small denomination. In the particular instance here illustrated the compartments 11 are for five-cent pieces commonly known as nickels, the compartments 12 being for dimes and the compartments 13 being adapted for quarters. I do not limit myself to coins of these particular denominations, as these are merely intended as typical.

Preferably as here shown each coin card is adapted to hold coins of an aggregate value of a predetermined round sum—in this particular instance one dollar. Thus the capacity of the book shown in Figures 1 and 2 is two dollars.

With the form of my device just mentioned, namely the one appearing in Figures 1 and 2, the book when filled with coins as herein contemplated may be handed in at a bank, the depositor being given proper credit in any appropriate way and receiving a new book in which to continue the saving of coins. If so desired, however, the book need not be used in connection with any commercial bank. It can be employed after the manner of a toy safe or other form of toy bank.

In the form shown in Figures 3 and 5, I

insert a memorandum sheet 14, provided with ruling 15. This ruling marks the memorandum sheet off into columns, as indicated in Figure 5. Thus prepared, the 5 memorandum sheet is well adapted to receive written memoranda of deposits, as indicated in Figure 5. In order to hold the memorandum sheet in position, it is provided with a reverting edge portion 16, which 10 is inserted beneath the adjacent edge portion of the coin card 10.

The form shown in Figures 4 and 6 differs from the one appearing in Figures 3 and 5, merely in the memorandum sheet. In the 15 form shown in Figures 4 and 6 the memorandum sheet comprises two leaves 17, 18, preferably integral as shown. These leaves are provided with a reverting edge portion 19, the latter being inserted beneath the adjacent edge portion of the coin card 10. Otherwise, this form of my bank book is 20 like that shown in Figures 3 and 5.

The form shown in Figures 3 and 5, like the one appearing in Figures 4 and 6, may 25 be used as a toy bank, in the manner above described with reference to the form shown in Figures 1 and 2. The presence of the memorandum sheet may be disregarded, or the memorandum sheet may be used for 30 memoranda independent of the savings, or it may be employed for notes in connection with the purpose of the book, considered as a toy bank.

As indicated in Figure 7, the book back 35 may be used to display legends of various kinds, for instance indicating the name of a commercial bank with which the book is associated, or indicating the name of the owner of the book, or suggesting economy or 40 thrift as a general rule of action.

I invite especial attention to the fact that my device presents considerable advantages, depending upon the manner in which it is used.

45 As a toy bank, it offers an incentive to save in that its coin compartments, so long as empty or partially empty, constantly suggest to the imaginative mind the propriety of filling the compartments in the 50 manner herein contemplated. Young persons especially are quick to recognize this mute appeal of the empty compartments. Then, after the coins are fitted into the compartments, it is simply human nature to let 55 them remain and to add to them, rather than

to withdraw them prematurely or irregularly.

As a bank book to be used in connection with a commercial bank, such for instance as a savings bank, it affords all of the usual 60 advantages of a deposit book of any usual kind. It may be employed, for instance, after the manner of a book filled with stamps and conforming to the system of a typical savings bank. Again, it may be used very much like the book of any ordinary commercial bank. Bills or checks may be deposited in the usual manner, and such deposits may be noted on the memorandum sheet; and this, too, independently of 70 whether or not any or all coins which may be carried by the book are deposited.

I do not limit myself to the precise construction shown, as variations may be made therefrom without departing from my invention, the scope of which is commensurate 75 with my claims.

I claim—

1. A bank book, comprising a book back and a coin card carried by said book back 80 and provided with coin compartments, and a memorandum sheet located within the book back and provided with a relatively large portion facing said coin card, said memorandum sheet being further provided with 85 a reverting portion extending between one edge portion of the coin card and the portion of the book back immediately adjacent.

2. A bank book, comprising a book back bent double and thus provided with a pair of 90 leaves facing each other and connected together by a fold, a pair of coin cards carried by said book back and provided with a number of separate coin compartments, each coin card being secured to the leaf immediately adjacent, so that the coin cards thus 95 face each other.

3. A bank book, comprising a book back bent double and thus provided with a pair 100 of leaves facing each other, a pair of coin cards each provided with coin compartments, the coin cards facing each other and being secured to the book back, and a memorandum sheet provided with a reverting edge portion extending between one edge 105 portion of the coin card and the portion of the book back immediately adjacent said edge portion of said coin card.

MALVIN LICHTER.
